R. F. LANDRUM

LOCK FOR ELECTRICAL CONNECTERS

Filed May 10, 1924

UNITED STATES PATENT OFFICE.

REGINALD FLEMING LANDRUM, OF NORFOLK, VIRGINIA, ASSIGNOR OF ONE-HALF TO
CHARLES W. CAMPBELL, OF NORFOLK, VIRGINIA.

LOCK FOR ELECTRICAL CONNECTERS.

Application filed May 10, 1924. Serial No. 712,441.

This invention relates in general to locks for electrical connectors, and is particularly designed for locking an electric lamp to its socket, although of course as well adapted 5 for use in locking similar fittings.

The object of the invention is to provide a device of this character which is effective to prevent the unauthorized or accidental removal of electric lamps from their sockets or 10 fittings and which is also of simple and durable construction, reliable and effective in operation and easy and comparatively inexpensive to manufacture and apply.

A further object is to provide a device of 15 this character and having the foregoing enumerated advantages and capacities and which may be readily released to permit authorized removal of the lamp from its socket or fitting.

20 Other objects and advantages reside in certain novel features of the construction, arrangement and combination of parts which will be hereinafter more fully described and particularly pointed out in the appended 25 claims, reference being had to the accompanying drawings forming a part of this specification, and in which:

Figure 1 is a view in perspective showing 30 an electric light socket equipped with the present invention, the electric lamp being shown prior to assembly.

Figure 2 is a view partly in elevation and partly in section illustrating the invention with the lamp partly introduced into its 35 socket,

Figure 3 is a view in perspective showing 40 the manner of releasing the lock, the casing of the socket being shown in dotted lines and partially omitted for the sake of illustration, and

Figure 4 is a perspective view showing the invention embodied in a different type of fitting or connector.

Referring to the drawings, and more particularly to Figures 1 to 3 inclusive, the numeral 10 designates an electric lamp socket which may be of any conventional type or construction. As usual the socket includes a threaded contact shell 11 which is enclosed in a casing 12, a lining 13 of insulation being provided between the casing 12 and the shell 11.

An electric lamp designated at 14 is provided, and as usual has an externally thread-

ed base or plug 15 adapted to be threaded 55 into the shell 11 of the socket 10.

Means is provided for locking the plug 15 in the socket so as to prevent accidental or unauthorized removal of the electric light or lamp 14. This means includes a locking 60 strip 16 inserted between the shell 11 and the insulation 13 of the casing 12. The inner end of the strip 16 is bent inwardly at right angles to provide an attaching portion 18 which extends through a slot or opening 65 formed in the shell 11 and is secured to the porcelain structure of the socket 10 in any suitable manner as by means of a screw 19. In this manner the locking strip 16 is firmly and rigidly held in position except that its 70 outer end may be flexed to some extent to provide for the releasing action to be later described. At the outer end of the locking strip 16 an inwardly extending locking lug 20 is provided. This lug 20 is formed with 75 an inclined or beveled surface 21 and with a sharp point 22. The beveled surface 21 permits the plug 15 of the lamp to be so turned as to introduce the lamp into the socket 10, but the point 22 prevents unauthorized or accidental removal of the plug 15 from the socket 10 since this point 22 bites into the material of the plug when the lamp and plug are turned to remove the lamp from the socket. The lug 20 is located 80 at the outer end of the shell 11 but the casing 12 and insulation 13 overlap the lug to conceal it.

When it is desired to remove the lamp or bulb from the socket a releasing tool 25 90 shown in Figure 3 must be employed, and includes a tapered and twisted shank 26 and an insulated handle member 27. The outer end of the twisted shank of the releasing tool is introduced between the lug 20, the strip 16 and the shell 11 and tool is then turned so as to pry or flex the lug 20 away from the plug 15 to permit the plug to be removed from the socket. The twist of the shank 26 permits the tool to pry the lug 20 100 away from the plug without the shank becoming bound in the structure of the socket.

The locking strip 16 and the locking lug 20 are constructed of tool steel and with such a construction the point or bit 22 of the locking lug will cut off the plug 15 of the electric lamp before permitting removal of the lamp from its socket. The shank 26 of the

releasing tool 25 is also constructed of tool steel to provide necessary torsional strength.

With this arrangement a simple, practical and comparatively inexpensive lock is had which is effective to prevent unauthorized or accidental removal of the lamp from its socket, and which effectively prevents theft of electric light bulbs. These advantages are had without altering or impairing in any way the structure or capacity of the lamp or socket to carry out its usual and customary functions.

The arrangement shown in Figure 4 is identical with that shown in Figures 1 to 3 except that the locking strips and its lug are organized with a different type of fitting, which is designated at 30. This fitting 30 includes a porcelain body 31 and a threaded shell 32 fitted in the porcelain body. The locking strip 16 has an attaching portion 18 as before, and this attaching portion is apertured to receive a screw 33 forming a part of the structure of the fitting 30. A nut 34 is threaded on the screw 33 and engages the attaching portion 18 to hold the locking strip in position.

It is to be understood that the present invention is adapted for use with any standard or known fitting or connector, and that various means may be provided for securing the locking strip in position.

I claim:—

1. A lock for securing a screw-threaded plug in a socket of an electrical connection

and comprising a locking strip extending lengthwise of the socket, connected thereto and concealed in the structure thereof, and a locking lug integral with the strip, said lug extending in a plane at right angles to the longitudinal axis of the socket and having a beveled edge permitting the plug to be threaded into the socket and also having a point, the mounting of the strip positioning the point so as to cause it to bite into the material of the plug to prevent removal of the plug from the socket.

2. A lock for securing a screw-threaded plug in a socket of an electrical connection and comprising a lock strip extending lengthwise of the socket and concealed in the structure thereof, means for fastening the inner end of the strip to the socket, and a locking lug integral with the outer end of the strip and located just inwardly of the outer end of the socket, said lug extending in a plane at right angles to the longitudinal axis of the socket and having a beveled edge permitting the plug to be threaded into the socket and also having a point, the strip being positioned and mounted to cause the point to bite into the material of the plug to prevent unauthorized removal of the plug from the socket, the portion of the strip adjacent the lug adapted to be pried outwardly by a suitable tool to disengage the point from the plug.

REGINALD FLEMING LANDRUM.
